UNITED STATES PATENT OFFICE.

KARL KAMMÜLLER, OF KARLSRUHE IN BADEN, GERMANY.

WATER CHAMBER.

Application filed January 28, 1927, Serial No. 164,268, and in Germany December 6, 1924.

My invention relates to water chambers for use as supplemental reservoirs, such as described in my application, Ser. No. 68,238, filed on Nov. 10, 1925, of which this is a continuation in part.

Such water chambers are used to supply water to turbines and similar water-consuming plants. In such plants, the water is usually conducted from a main reservoir to a supply gallery through a more or less steep drop-pipe. These auxiliary water-chambers are usually constructed with a vertical shaft and an upper and lower compartment, the vertical shaft communicating with these compartments and the supply gallery.

I have found that for the economic operation of such water chambers, it is necessary that the velocity of the flow of water in the supply gallery should as quickly as possible accommodate itself to the variations in the load, in which case, the compartments of the water chamber can be made of smaller dimensions than is otherwise necessary. The velocity of the flow of water in the supply gallery depends on the difference of pressure in the water chamber, which difference of pressure is produced by the ascending and descending column of water in the shaft of the water chamber, and it is of importance to maintain as great a difference of pressure as possible, if the greatest efficiency is to be obtained with the greatest economy in space.

Such economy in space has already been effected by the provision in the upper compartment of the water-chamber, of an overflow-sill, whereby a higher water column is initially produced. Now, I have found that by the arrangement of a similar sill for the lower compartment of the water-chamber, I can still further improve the efficiency of the device, tho' the effect of the sill in the lower compartment differs from that of the overflow-sill in the upper compartment.

For a better understanding of my invention, I refer to the accompanying drawing, in which I have illustrated my invention and in which the sectional Fig. 1 shows the water-chamber provided with the upper and lower compartment and the connecting shaft, the two compartments being formed in the rock; Fig. 2 is a section along line 2—2 in Fig. 1; Figs. 3 and 4 are sectional views of a modification, the shaft being shown arranged laterally of said compartment, Fig. 4 being a section along line 4—4 in Fig. 3. Fig. 5 is

a vertical sectional view of a modification, in which the compartments of the water chamber are above ground, Fig. 6 is a horizontal section along line 6—6 in Fig. 5.

According to Fig. 1, A is the upper compartment of the water-chamber equipped with the overflow-sill *a*. S is the shaft and B the lower compartment shown in line with the shaft. At *a'* is shown an outlet through which compartment A may empty.

The lower compartment B, which may be merely an enlargement of the gallery roof, is closed toward shaft S by a sill *b* which, as distinguished from the overflow-sill *a* in the upper chamber A, may be referred to as a suction-sill.

During normal operation the water in the shaft S is at a height equal to that of the water in the reservoir from which the water flows into the gallery G from the right, considering Fig. 1 except for the loss occurring by friction of the water in the gallery. If the load varies, the velocity of the water in the gallery cannot suddenly adapt itself to the changed demand; the water chamber B then acts as an elastic member, taking up excess of water from the gallery when the load decreases, and letting water pass into the gallery when the load increases, until the velocity of water passing through the gallery has adapted itself to the new load.

Now, if, while the chamber is filled, there should occur a sudden increase in the load, because of the greater demand, the water level in the shaft S will drop quickly to the lower edge of suction sill *b* exposing said lower edge. In that case, air will be sucked around the sill into the compartment B, and the demand for water will be supplied from the water in the compartment B, and as long as water flows from said compartment, the water level in the shaft S will be constantly automatically regulated to the same height, since every change in the water level will immediately provoke a corresponding opposing change of the admission of air into the compartment B.

The object of the suction sill is to lower the level in the shaft S as quickly as possible; the quicker the level in the shaft S drops, the quicker is the acceleration of the water in the gallery, and the less space is required for the water chamber or the lower compartment B. Were the suction sill omitted, the lever in the shaft S upon an increase in the load

would first drop only to the upper edge of compartment B, and then drop slowly together with the falling of level in this compartment. The suction sill, therefore, causes 5 a more rapid acceleration in the flow in the gallery and therefore, a definite and computable reduction in the volume of the compartment B.

Thus, by the simple arrangement of the 10 suction-sill b, there is obtained, the effect that aside from the rapid lowering of the water level in the shaft S during the entire period of the emptying of the compartment B, the greatest possible drop of pressure becomes 15 available for the acceleration of the water in the supply gallery so that the acceleration period is considerably shortened and economy in space is obtained.

Instead of permitting the air to be sucked 20 around the lower edge of the sill b through the mass of water, which thereby would become stirred up, an air-duct c may be provided in the sill b, as shown in Fig. 1, which air-duct permits the air to pass into the upper 25 portion of the compartment B. The water level, therefore, will remain undisturbed, and further economy in space may be obtained thereby, as the compartment may be of still smaller height.

30 To enable the re-filling of the compartment B, there is provided at its upper end an opening d for the escape of air which opening is so dimensioned as to enable the slow filling of the compartment, while preventing 35 any noticeable admission of air during the rapid drop of the water column in the shaft.

The arrangement and operation of the 40 modified device shown in Figs. 2-4 are the same as the one shown in Fig. 1, except that the shaft S, instead of being arranged in line with the compartment B is arranged laterally thereof, as clearly shown in the drawings. This modification shows the chamber B as an elongated relatively narrow chamber, but obviously the chamber may be 45 designed to meet any specified need for a reserve water supply. This modification has no air duct c such as shown in Fig. 1.

50 In the modification shown in Figs. 5 and 6, in which the two compartments of the water-chamber are shown above ground, the upper compartment is designated by A', the lower compartment by B', and the gallery G' whereas S' is the shaft, which passes through the two chambers, terminating in compartment B' at b'.

The operation is the same as in the construction shown in Figs. 1-4. Upon a sudden increase in the load, the water level in shaft S' will rapidly drop to the bottom edge (b') 60 of shaft S' exposing said edges with the result that water will flow from compartment B'. Through a pipe c' shown in Fig. 5, air will be sucked around the bottom edge b' and will flow into the upper portion of compartment B'. 65

At the upper end of compartment B' are provided openings d' through which the air may escape so that the compartment B' may be refilled. 70

I claim:

1. In a water chamber of the type described, a shaft, a reservoir compartment communicating with the lower end of the said shaft, said lower end projecting into 75 said reservoir compartment.

2. In a water chamber of the type described, a shaft, a reservoir compartment communicating with the upper end of said shaft, and a second reservoir compartment 80 communicating with the lower end of said shaft, the latter extending through said two compartments and terminating intermediate the top and bottom portion of each compartment. 85

3. In a water chamber of the type described, a shaft, a reservoir compartment communicating with the upper end of said shaft, a second reservoir compartment communicating with the lower end of said shaft, 90 the latter extending through both said compartments and terminating intermediate the top and bottom portion of said second compartment, and an air conduit leading from the lower edge of the shaft to the upper portion 95 of said second compartment.

4. In a water chamber of the type described, a shaft, a reservoir compartment communicating with the lower end of said shaft, the lower edge of said shaft extending 100 into said compartment, and a narrow air passage leading from said edge to the upper portion of said compartment.

5. In a water chamber of the type described, a shaft, a reservoir compartment 105 communicating with the upper end of said shaft, a reservoir compartment communicating with the lower end of said shaft said lower end of the shaft extending into said lower compartment. 110

In testimony whereof I affix my signature.

KARL KAMMÜLLER.
